REFRIGERATING APPARATUS

Theodore L. Chisholm, Pleasant Ridge, Mich., assignor, by mesne assignments, to General Motors Corporation, a corporation of Delaware

Application September 29, 1930, Serial No. 485,176

1 Claim. (Cl. 137—68)

This invention relates to refrigerating systems and particularly to the control of refrigerant passing through the evaporator thereof.

In refrigerating systems wherein a valve is provided for controlling the flow of refrigerant, such a valve, after considerable use, becomes worn due to the velocity of refrigerant flowing past the same during its open position, and will not properly engage its seat thus permitting refrigerant to leak, when the valve is in closed position. When this condition occurs it is necessary to remove the valve and replace it with a new one or reface the surfaces thereof.

In the particular embodiment illustrated, such valve is employed for controlling the flow of refrigerant from the high pressure side of the refrigerating system to the low pressure side of such system. Heretofore when it was necessary to remove such a valve all refrigerant within a part of the system was required to be withdrawn therefrom and pumped or circulated to other parts of the system which, in the case of large reservoirs, required a considerable amount of time and rendered a service call costly. To this end it is one of the objects of my invention to provide improved means for preventing the escape of refrigerant from the system when the valve, which ordinarily controls such flow, is removed.

A further object of the invention is to provide a refrigerating system with a supplementing valve operated automatically to prevent the escape of refrigerant from the system when a part of the system is opened to remove the valve, controlling the flow of refrigerant therein, to be replaced or refaced.

A further object of the invention is to provide means including a valve for separating the low side from the high side of a refrigerating system which valve can be quickly removed without disassembling any portion of the system while automatically preventing the loss of refrigerant contained in the system so that the valve can be replaced in a minimum amount of time.

Further objects and advantages of the present invention will be apparent from the following description, reference being had to the accompanying drawings, wherein a preferred form of the present invention is clearly shown.

In the drawings:

Fig. 1 is a fragmentary cross-sectional view in a vertical plane of an evaporator constructed in accordance with the present invention connected to a refrigerating system shown diagrammatically;

Fig. 2 is an enlarged sectional view of a portion of the evaporator taken on the lines 2—2 of Fig. 1;

Fig. 3 is a sectional view of a portion of the evaporator showing certain parts thereof removed and showing the shut-off valve in closed position; and

Fig. 4 is a view of a portion of the evaporator taken on the lines 4—4 of Fig. 1.

Referring to the drawings 10 designates a compressor driven by an electric motor 11 for withdrawing evaporated refrigerant from an evaporator 12. The refrigerant gas to be compressed enters compressor 10 through pipe 13 and is expelled through a pipe 14. The compressed refrigerant passes through the condenser 15 where it is cooled, in any suitable manner, and liquefies and from thence it passes into the receiver 16. The liquefied refrigerant then flows to evaporator 12 through pipe 17. The motor which actuates the compressor 10 may be controlled in any suitable manner. For example motor 11 may be controlled by a switch 18 responsive to pressures in the low pressure side of the system.

The improved mechanism herein disclosed may be used in various types of refrigerating systems. In the present embodiment, I have shown a valve as being responsive to a certain condition in the refrigerating system and more specifically, the valve is shown responsive to a predetermined level of liquid refrigerant within an evaporator.

Referring more particularly to Fig. 1 evaporator 12 comprises a header 20 and an end cover 21 attached to the header by bolts 22. The end cover 21 is provided with an inwardly extending boss 23. Boss 23 is provided with a cylindrical opening 24 the inner end of which is provided with a relatively small opening 25 and a valve seat 26. A valve 27 cooperates with the valve seat 26 and has a stem 28 extending through the opening 25. The opening 24 is internally threaded to receive a screw plug 29 and is counterbored at 31 for the purpose of permitting a sealing washer of suitable material such as for example as a lead washer 32 to be clamped between the head of the plug 29 and boss 23 to prevent the escape of refrigerant from the evaporator at this point. A spring 33 is interposed between the back of valve 27 and plug 29 and normally maintains the valve 27 upon its seat 26. The boss 23 is also provided with a horizontal passage 34 communicating with a vertical passage 35 which in turn communicates with the opening 24. Passage 34 is en-

larged and screw threaded near the face of end cover 21 to receive a combined coupling and shut-off valve 36 which is connected with pipe 17 of the refrigerant liquefying unit. Details of the 5 combined coupling and shut-off valve have been omitted from the drawings and this valve may be of any conventional structure suitable for the purpose. Cover 21 is also provided with a hole 37 which receives an inwardly extending pipe 38 10 and is connected by coupling 39 to pipe 18, the hole 37 providing an outlet for refrigerant gas evaporated in the evaporator 12.

Float lever 41 is pivoted at 42, which pivot is supported by ears 43 formed on boss 23, and carries float ball 44. Float lever 41 has a downwardly projecting arm 45 which is adapted to engage with the stem 28 of valve 27 to move the valve away from its seat 26 whereby liquid refrigerant will pass through opening 25 into the 20 header. After the level of the liquid refrigerant within header 20 rises to a certain height the arm 45 of lever 41 will move far enough to permit spring 33 to move valve 27 to closed position. In such a structure the valve is opened by the float 25 but slightly when maintaining a certain predetermined level and liquid refrigerant flows past the valve into the header at a high velocity. The velocity of this liquid refrigerant is so great that after the valve has been in use a short period of 30 time it becomes worn and will not seat properly. This improper seating of the valve permits liquid refrigerant to leak into the header when the valve is closed thus causing inefficient operation of the refrigerant liquefying or circulating unit 35 necessitating replacement of the valve.

My invention is therefore particularly directed to an improved system provided with automatically operated means for sealing refrigerant contained therein when the valve is rendered inoperative and is removed. In carrying out the invention my improved system includes an evaporator structure provided with a circular plate 47 carried on lugs 48 which may be formed on the inner face of boss 23. Plate 47 has a circular 40 tapered portion 49 providing a valve which is adapted to engage a circular seat 51. The seat 51 is formed by a raised annular portion protruding from the inner face of boss 23 and located between the lugs 48. One end of a spring 52 45 abuts against the plate 47 and has its other end secured, by screws 53 to the boss 23. As apparent from the drawings, plate 47 and spring 52 are slidably carried between the stem portion 28 of valve 27 and arm 45 of float lever 41. The valve 55 50 is normally maintained in open position to permit the ingress of liquid refrigerant under control of valve 27. The spring 52 is of less tension than spring 33 but of sufficient tension to positively and automatically seat valve 49 upon 60 its seat 51 when the tension of spring 33 is lessened or when spring 33 is removed.

The height of the liquid level within header 20 is controlled by the tension of spring 33 which must also overcome the tension of spring 52. 65 The spring 33 can be exchanged for one of greater or less tension when desired for controlling the force required to open or close the valve 27.

In the present embodiment the improved structure provides a valve separating the high and low 70 sides of a refrigerating system which valve is readily removable from the exterior of the header without dismantling the evaporator. The valve 27 may be readily removed from the header when

not operating correctly without withdrawing refrigerant contained in the evaporator and pumping this refrigerant to other parts or elements of the system. In order to remove the valve 27 from the header 20 when not functioning properly 5 the manual shut-off valve, contained in the coupling 36 connecting the liquid refrigerant supply pipe 17 to the evaporator, is closed. Closing of valve 36 prevents refrigerant from flowing into the opening 24 and the plug 28 may then be removed from the end cover 21. Loosening of plug 28 releases the tension of spring 33 and thereby permits spring 52 to force valve 49, on plate 47, into engagement with its seat 51. It is to be understood that the construction and arrangement 15 of the parts permits valve 49 to close automatically when valve 27 is moved from its controlling position or when spring 33 is rendered inoperative for closing valve 27. This preferably occurs as soon as the plug 28 is loosened slightly and 20 prior to the time the plug is entirely removed from the opening 24. Thus refrigerant contained in the evaporator and the remainder of the system is prevented from escaping therefrom. The opening 24 and passages 34 and 35 are made 25 small, therefore the amount of refrigerant contained in these passages and which refrigerant escapes when the plug 28 and valve 27 are removed, is negligible and will not cause injurious effects to the service man. 30

From the foregoing it is apparent that I have provided an improved refrigerating system employing a valve therein for separating the high and low pressure sides of the system which valve can be quickly and readily removed without the 35 necessity of withdrawing refrigerant from the evaporator which evaporator is also provided with automatically operated means for preventing the loss of refrigerant from the system.

While the form of embodiment of the invention 40 as herein disclosed, constitutes a preferred form, it is to be understood that other forms might be adopted, all coming within the scope of the claim which follows.

What is claimed is as follows:

An evaporator of a refrigerating system comprising in combination, walls defining a closed chamber providing a reservoir for liquid refrigerant, one wall of said chamber having a passage formed therein for the ingress of liquid refrigerant to the reservoir, a valve within the confines of said chamber walls and positioned in the passage in said one chamber wall, means for normally maintaining said valve closed, a float within said chamber responsive to the level of liquid refrigerant therein for actuating said valve from its normal closed position to permit flow of refrigerant from said passage to the interior of said closed chamber, said valve being removable from said chamber and said passage without removing its actuating means, a second valve for controlling the flow of refrigerant through said passage, said second valve being located between said first named valve and its actuating means, said second valve being normally maintained in open position by said first named valve, and mechanism for at all times biasing said second valve to closed position and for closing said second valve automatically during the act of removing said first valve from said chamber and said passage to prevent the escape of refrigerant from said chamber or reservoir. 70
